UNITED STATES PATENT OFFICE.

FRIEDRICH ERNST FERDINAND NEUMANN, OF WANDSBEK, NEAR HAMBURG, GERMANY.

MANUFACTURE OF COCOA PASTE.

No. 801,259.

Specification of Letters Patent.

Patented Oct. 10, 1905.

Application filed May 2, 1903. Serial No. 155,403.

To all whom it may concern:

Be it known that I, FRIEDRICH ERNST FERDINAND NEUMANN, a subject of the German Emperor, and a resident of Wandsbek, near Hamburg, in the German Empire, have invented certain new and useful Improvements Relating to the Manufacture of Cocoa Paste, of which the following is a specification.

The present invention relates to improvements in roller-mills for the manufacture of cocoa paste from fat-containing cocoa-beans. The object of the improvements is to provide a roller-mill which allows of the passing of the cocoa-beans and the pulp obtained therefrom between pairs of roughened rollers arranged vertically below and in close proximity to each other and the conveying of the material that has passed said roller pairs in a lateral or horizontal direction to one or more other rollers.

In the accompanying drawings, Figure 1 is a vertical cross-section of a roller-mill constructed in accordance with and embodying my invention. Fig. 2 is a sectional view of the feed-hopper, taken on the line I II, Fig. 1; and Fig. 3 is a side view showing the driveage.

Similar letters of reference refer to similar parts throughout the several figures.

In a suitable frame A are mounted several (say two) pairs of rollers *a*, one pair of rollers *a* vertically beneath the other pair. The upper pair of rollers *a* are geared together by gear-wheels *h* *i*, mounted on their shafts and are driven by belt-pulley *g*. The lower rollers *a* are driven by *l* and *m* and the transfer-roller *c* by belt-pulley *k*. These belt-pulleys *k*, *l*, and *m* are of different sizes to give different speeds to their respective rollers. The roller *c* is an additional one to effect the grinding to a finer degree and at the same time act as a transfer-roller, thereby forming the equivalent of a six-roller mill, dispensing with one roll and a pair of scrapers. In order to transfer the paste to the roll *c*, the right-hand lower roller *a* rotates faster than the left-hand one and lateral roller *c* rotates faster than the said right-hand lower roller *a*. Beside the rollers, heating-chambers *b*, which may conveniently be of curved formation, may be arranged in the manner shown by dotted lines. Below some of the rollers are mounted scrapers *c*, and above the upper pair of rollers *a* is situated the feed-hopper *d*, provided with a

feed-roller *f* at its lower portion for regulating the discharge of the cocoa-beans.

A special feature of the feed-hopper is the provision of heating-passages *d'* in or along the walls of the hopper and also transversely across the same, Fig. 2, these passages being connected one with the other by means of ribs or plates *d''*, so as to insure a better distribution of the heat. By means of these heating-passages *d'* and ribs or plates *d''*, which act as radiators, the cocoa-beans may be preparatorily heated in such a manner as to render any special heating of the rollers *a* unnecessary. Nevertheless the heating-chambers *b* may be provided in proximity to the rollers for use in case of need. The heating may be effected by means of steam or hot water, these heating media being conducted through the heating passages or chambers in any convenient manner. (Not shown in the drawings.)

The cocoa-beans introduced into the feed-hopper *d* first of all fall, either in a hot or cold condition, according to requirements, between the two upper rollers *a*, which break up the woody fibers of the beans, while the cocoa butter is speedily melted owing to the great heat. The pulverized and melted material is removed from the rollers *a* by the scrapers *c* and falls upon the second pair of rollers *a*, where it is subjected to a further reducing and grinding process, and finally it is taken up by the lateral roller *c*, from which it is removed by the scraper *c* as cocoa paste. By reason of the increasing speed of the three lower rollers the paste is taken from one to the other, working over to the roller *c*, where it is scraped off.

If it is desired to obtain a somewhat coarse cocoa paste, two pairs of rollers arranged one below the other will be sufficient. They may be supplemented by one or more lateral rollers, according to the degree of fineness desired.

The constructional details of the means described above may be modified in numerous ways—for example, the heating of the rollers may be effected in various manners, or, as above-stated, may be dispensed with altogether if the cocoa-beans are supplied in a heated state.

Owing to the fact that the cocoa-beans and the pulp arising therefrom are carried between and around the rollers in a short path for the purpose of being converted into cocoa

mass, the process of conversion is so speedily effected that the paste does not lose any or nearly any of the aroma.

Having fully described my invention, what I claim, and desire to secure by Letters Patent, is—

1. In a machine of the class described, the combination with a hollow feed-hopper having a longitudinal partition and a plurality of transverse partitions, a pair of grinding-rollers beneath the hopper, a similar pair of grinding-rollers directly beneath the first pair, scrapers to engage each of the upper rollers and contacting with them in the angle formed between them, whereby the material will be scraped therefrom and fall on the lower rollers in the angle between them, a lateral roller contacting with one of the lower rollers, substantially as described.
2. In a machine of the class described, the combination with a hollow feed-hopper for the reception and circulation of a heating medium therethrough; of a pair of crushing-rollers beneath the hopper, a radiator oppo-

site each roller to heat the material on the 25 rollers, a second pair of crushing-rollers below the first pair, a lateral roller coöperating with one of the latter to form a series of three rollers and a radiator opposite each end roller of the series, substantially as described. 30

3. In a machine of the class described, the combination with a feed-hopper having hollow walls and a hollow longitudinal partition connecting opposite hollow walls and transverse solid partitions, whereby the feed-hopper can 35 be heated by means of hot water or steam, a feed-roll below and at one side of the hopper, a set of coöperating crushing-rollers below the hopper, and a second set of coöperating crushing-rollers below the first set and 40 containing a greater number of rollers, and a heat-radiator opposite each end of each set of rollers, substantially as described.

FRIEDRICH ERNST FERDINAND NEUMANN.
